UNITED STATES PATENT OFFICE

BOODHUN BAICHUN MAHATHO, OF OVERPORT, DURBAN, UNION OF SOUTH AFRICA

TELLURIAN

Application filed July 27, 1929, Serial No. 381,615, and in the Union of South Africa, August 22, 1928.

This invention relates to the provision of mechanical means whereby the movements of the heavenly bodies may be demonstrated and has for its object to provide means for illustrating more particularly the movements of the moon in relation to the earth and of both relative to the sun.

A further feature of the invention is the provision of means whereby at a glance may be seen the days and months as they occur as well as the solstices and equinoxes.

Provision is also made for automatically illustrating the parts of the earth which are in light and in darkness during the 24 hours.

In accordance with my invention I provide a pedestal or base on which I erect gearing consisting of a train of wheels operated by a handle, and I provide that certain pinions shall engage a rack to which is secured a tower of suitable shape, the whole capable of revolving on the pedestal. Within the tower and engaging the aforementioned train of wheels through the medium of beveled gears or the like, I erect a shaft terminating above the tower in a sphere representing the sun. At a suitable height on this shaft I mount further beveled gears by means of which I transmit motion to a shaft disposed horizontally in respect of the tower. This horizontal shaft may conveniently be housed in a casing which forms a part of the supporting frame to other parts of the instrument and which frame may be secured to the tower by brackets or the like. The horizontal shaft carries beveled gears at its outer end and thereby motion is imparted to the shaft which represents the axis of the earth. In addition to carrying the sphere representing the earth this shaft also supports a frame in which is pivoted a plate or plates encircling the earth sphere and which, being hung above the centre of gravity, will always maintain a vertical position or one perpendicular to rays from the sphere representing the sun.

The aforementioned frame also carries beveled gears through which motion is imparted to a worm and worm wheel to the shaft or spindle by which is attached an arm carrying the sphere representing the moon.

A gap is made in the housing to the hori-

zontal shaft and therein is provided a worm which operates a worm wheel to the spindle of which is attached a dial on which is recorded the months, days, solstices, and equinoxes. The same spindle operates a cam or eccentric attached to the worm wheel, and is provided with a grooved rim in which operates a vertically disposed member whose lower end is pivoted to a bracket or the like on the wall of the tower, and to whose upper end is attached a rod or like member having the other end secured to the top of the moon spindle or shaft or to any other convenient part of the earth sphere frame. A tension spring is connected between the frame and this member to maintain contact at all times between it and the cam or eccentric. The to and fro movement of the vertically disposed member caused by the cam excites similar movement in the earth sphere's axial shaft thereby providing for the varying inclination of the earth in its progress round the sun, the inclination being facilitated by the provision of a universal joint in the axial shafting.

In order that my invention may be readily understood and carried into practice, reference is hereby made to the accompanying sheet of drawings wherein Fig. 1 is an elevational view of the invention, Fig. 2 is a sectional elevation of the tower and internal and adjacent mechanism with the ball or sphere representing the earth removed, and Fig. 3 is an elevational view of the ball or sphere with attendant sphere representing the moon, supporting frame and gearing.

Referring to these drawings wherein like reference numbers indicate the same parts wherever occurring throughout all the views, 1 denotes the base or pedestal on which is mounted the train of wheels 2 which is operated by the handle 3 and imparts motion at the required speed and ratio to the tower 4 through the rack 5 and pinion 6 and to the central vertical shaft 7 which supports the globe 8 representing the sun. The central vertical shaft 7 further imparts motion by means of beveled gears 9 to the horizontal shaft 10 which by means of the gears 11 imparts motion to the sphere 12 which repre-

sents the earth, through the axis 13 which at its lower end is provided with a universal joint 14 to permit of the axis 13 changing the angle of its inclination.

5 The axis 13 works in bearings in a frame 15 which surrounds the sphere 12 and which carries on its upper member 16 gears 17 which transmit motion from the axis 13 to a worm 18 which drives a worm wheel 19 secured to 10 the shaft 20. The shaft 20 has attached to it and therefore revolving with it an arm 21 at the end of which is mounted the small sphere 22 representing the moon.

In order to effect the change in the inclination 15 of the axis 13 the top of the shaft 20 is connected by means of a suitable collar 23 or other convenient means to a rod 24 which is secured at its other end to the end of a more or less vertical member 25 pivoted at 20 26 and engaging the hollow rim of a cam or eccentric 27, contact being maintained by the provision of a tension spring 28 secured at a convenient point in the frame or supporting members 29. The cam or eccentric 25 27 is attached to a worm wheel 30 which is driven by a worm 31 on the shaft 10. Mounted 30 on and revolving with the shaft 32, on which the worm wheel 30 is also secured, is a dial 33 on which are set out divisions 34 for the twelve months of the year and further spaces are provided at 35 for indicating by means of the pointer 36 the solstices and equinoxes.

To indicate the line of demarcation 35 between light and darkness a plate or two half plates 37 are hung in the frame 15 and they encircle the sphere 12. By reason of their being pivoted at 38 above the centre of gravity this plate or plates 37 will always be in 40 a perpendicular position relative to the rays from the sphere 8 representing the sun irrespective of the inclination or otherwise of the axis 13.

In operation the sphere 8 may be represented 45 most effectively by an illuminated globe and the sphere 12 by the known type of the world, while the sphere 22 may have the half facing the earth colored white and the other half a dark color, as shown in Fig. 1. The correct setting of the spheres and dials 50 having been determined the handle 3 is operated and results in the slow revolution of the tower 4 which carries with it the frame 29 as well as the earth 12 and the moon 22. In 55 addition to the revolution of these satellites round the sun 8 the earth 12 is caused to rotate on its axis 13 by means of the gears 11 while the gears 17 give motion to the worm 18 causing the revolution of the worm wheel 19 60 which having a ratio of 28 to one causes the moon 22 to revolve round the earth 12 once in 28 days.

A worm 31 is provided in the shaft 10. This causes the worm wheel 30 to revolve 65 carrying with it the dial 33 and the cam or

eccentric 27 which in turn imparts to and fro motion to the member 25 and by means of the connecting rod 24 to the frame 15 and with it the axis 13 of the earth 12, such movement being made possible by the provision of the 70 universal joint 14.

It will be seen from the above that I have by my invention provided a simple and effective means of illustrating and demonstrating the movements of certain of the heavenly 75 bodies in relation to one another and to the sun, my invention clearly illustrating (1) the causes of day and night, (2) the causes of long and short days, (3) the seasons, (4) the solstices and equinoxes, (5) the months of the 80 year, (6) the annual revolution, (7) the days of the year, (8) the revolution of the moon, (9) the phases of the moon, (10) the possibility of eclipses, and (11) morning, evening, sunset or dawn at any particular place. 85

I claim:—

1. A tellurian adapted to demonstrate the movements of the moon in relation to the earth and of both in relation to the sun, comprising a central revolving support, mechanical means consisting of trains of wheels, bevelled gears, shafting, and spheres to represent the earth, moon and sun, attached to and working from said support, cam mechanism to vary the inclination of one of the spheres, 90 and a graduated dial rotated by said shafting to indicate in correct succession certain divisions of time corresponding to the variable relative position of the sun, earth and moon to one another. 95

2. A tellurian adapted to demonstrate the movements of the moon in relation to the earth and of both in relation to the sun, comprising a central revolving support, mechanical means consisting of trains of wheels, bevelled gears, shafting and three spheres to represent the earth, moon and sun, attached to and working from said support, cam mechanism to vary the inclination of the axis of the sphere representing the earth, a graduated 110 revolving dial actuated from said support marked with certain divisions of time corresponding to the variable relative position of the sun, earth and moon to one another, and a fixed pointer to indicate any desired point in time of the calendar year marked upon said dial, in proper correspondence with the relative positions of the three spheres to one another. 115

3. A tellurian adapted to demonstrate the movements of the moon, in relation to the earth and of both in relation to the sun, comprising a central revolving support, mechanical means consisting of trains of wheels, bevelled gears, shafting, and spheres to represent the earth, moon and sun, attached to and working from said support, cam mechanism to vary the inclination of the sphere representing the earth, a universal joint to permit of such inclination, a graduated dial 125 130

operated by said mechanical means and a pointer to indicate on said dial certain divisions of time corresponding to the variable relative position of the sun, earth and moon to one another.

4. A tellurian of the character described comprising a member representing the sun, movable members representing the moon and the earth, means for rotating the sun member, gear—operated from said means for rotating the earth member about its axis, a universal joint between the earth member and said gear to permit transmission of rotary motion and variation of the angle of inclination of said axis relatively to the gear, a worm drive for rotating the moon member about said axis in proportion to the motion of said axis relatively to the gear, a worm for operating said dial, and means for operating said dial.
